ASSEMBLY OF A HEAD AND REFLECTOR FOR A LAMP

Filed Feb. 5, 1931

By *Arthur R. Woolfolk*,
attorney

UNITED STATES PATENT OFFICE

ALWIN G. STEINMAYER, OF MILWAUKEE, WISCONSIN, ASSIGNOR TO LINE MATERIAL COMPANY, OF SOUTH MILWAUKEE, WISCONSIN, A CORPORATION OF DELAWARE

ASSEMBLY OF A HEAD AND REFLECTOR FOR A LAMP

Application filed February 5, 1931. Serial No. 513,532.

This invention relates to an assembly of a head and reflector for a lamp.

Objects of this invention are to provide an assembly of a porcelain head and reflector

5 for a lamp in which the reflector is provided with a screw-threaded neck, and in which the porcelain head is provided with screw threads directly formed in the porcelain head and cooperating with the threads of the reflector

10 so that auxiliary attaching means for holding the reflector and head together are avoided.

Further objects are to provide a porcelain head having lamp receiving means and having a downwardly extending, integral, internally threaded flange adapted to receive the threaded neck of a reflector, and in which locking means are provided for locking the reflector against rotation to thereby prevent 15 inadvertent unscrewing of the reflector from the head.

In greater detail, further objects of this invention are to provide a porcelain head having a downwardly extending, internally 20 threaded flange adapted to receive the threaded neck of a reflector, in which clamping means are provided for clamping the neck of the reflector to the head to prevent inadvertent unscrewing, in which the clamping means 25 is externally operable, and in which the entire clamping means is held in assembled position by means of an externally manipulable screw-threaded shaft.

An embodiment of the invention is shown 30 in the accompanying drawing, in which:

Figure 1 is a view of the assembly of head and reflector with parts broken away and with parts in section.

Figure 2 is a fragmentary view taken on 35 the plane indicated by the line 2—2 of Figure 1.

Figure 3 is a perspective enlarged view of the clamping member.

Figure 4 is a perspective enlarged view of 40 the guiding member.

Referring to the drawing, it will be seen 45 that the assembly comprises a porcelain head 1 which may be carried from any suitable suspension member, or other suitable member, indicated by the reference character 2.

This porcelain head is provided with an integrally formed downwardly extending flange 3 and is further provided with an integral outwardly and downwardly extending drip flange 4.

The porcelain head carries lamp receiving means such as the lamp socket 5, for instance.

This invention contemplates the formation of internal threads 6 directly formed in the 60 downwardly extending flange 3. The threads 6 are preferably devoid of sharp corner portions, although the invention in its broadest aspect is not limited to this particular feature. For example, as shown in Figure 65 1, the threads 6 are provided with rounded channels and ridges. This construction has been found most satisfactory and avoids chipping or cracking of the threaded portion. Obviously another shape of thread could be 70 used if so desired, but this shape is preferable.

The reflector 7 may be of metal or of other material, and is provided with a metal neck 8.

It is preferable in forming the reflector to 75 construct the body portion 7 thereof of metal and to clamp this body portion to the metal neck 8 by the folded portion 9, preferably formed on the metal neck portion. This construction simplifies the manufacture of the 80 reflector.

Also it is preferable to provide an inwardly directed flange 10 at the upper edge of the metal neck 8, as shown in Figure 1, to reinforce this neck and to provide a portion 85 against which the clamping member herein-after described may bear, although obviously the clamping member might bear directly upon the threaded portion of the neck 8 without departing from the spirit of this invention.

It is to be noted from Figure 1 that the flange 3 of the porcelain reflector has a slot 11 formed therein and extending upwardly from its bottom edge and opening inwardly 95 of the flange. This slot receives the base portion 12 of the guiding member. This guiding member, as shown most clearly in Figure 4, is provided with an aperture 13 in its base portion and is preferably provided with 100

a pair of spaced arms 14 which project inwardly of the flange 3, as shown in Figure 1.

The clamping member 15 may consist of a small plate which is provided with notches 16 which slidably receive the arms 14 of the clamping member. It is also provided with a threaded aperture 17 and with an inwardly turned lip 18 adapted to be located just below the flange 10 formed on the neck 8 of the reflector, see Figure 1.

A shaft 19 projects through the flange 3 and is provided with a screw-threaded, preferably enlarged, portion 20 located inwardly of the flange and with a manipulating thumb piece or head 21 located externally of the flange. The head is secured to the shaft in any suitable manner, as by pinning, as indicated in Figure 1. Suitable washers are preferably provided, as shown in Figure 1, to lessen friction and distribute the pressure. The shaft 19 extends through the aperture 13 of the base 12 of the guiding member and thus holds the guiding member in assembled position with its base seated within the slot 11. The threaded portion 20 is screwed into the threaded aperture 17 of the clamping member.

In using the apparatus, the clamping member 15 is moved inwardly with respect to the flange 3 by rotating the manually manipulable external member 21. Thereafter the reflector is screwed into position, as shown in Figure 1, preferably with the upper portion of the folded portion 9, which forms a shoulder 22, directly engaging the bottom edge of the flange 3 of the porcelain reflector. Thereafter the clamping member 15 is moved into binding engagement with the flange 10 by rotating the member 21, see Figure 1. This clamping member 15 thus locks the reflector against rotation and thereby prevents inadvertent unscrewing of the reflector from the porcelain head.

When it is considered that in the manufacture of porcelain articles that slight variations occur, it will be immediately appreciated that it is preferable to provide a fairly free fit between the threaded portion 6 of the flange of the porcelain head and the threaded portion or neck 8 of the reflector. However, this invention does not allow loosening or unscrewing to occur, although there may be a fairly free fit between the metal neck of the reflector and the porcelain head. The invention provides clamping means which locks the reflector against rotation and thus prevents unscrewing, even when the assembly is swayed or jarred by gusty winds or through other means. Instead this invention insures the correct positioning of the reflector at all times.

This invention also provides a porcelain reflector in which the threads are directly formed therein thereby avoiding the heretofore complicated constructions.

Although this invention has been described in considerable detail, it is to be understood that such description is intended as illustrative rather than limiting, as the invention may be variously embodied and is to be interpreted as claimed.

I claim:

1. An assembly of a porcelain head and a reflector for a lamp comprising a porcelain head having a closed upper end provided with suspension means and having an outwardly projecting drip flange and having a downwardly projecting flange, said downwardly projecting flange having internal screw threads directly formed therein, lamp receiving means carried by said porcelain head, a reflector having a metallic neck portion provided with external threads fitting the internal threads of the downwardly extending flange of said porcelain reflector, and means for locking the reflector against rotation, said means having an external manipulating portion located below said drip flange.

2. An assembly of a head and reflector for a lamp comprising a head having a downwardly projecting flange having internal threads, said head having means for receiving the lamp, a reflector having a neck provided with external threads cooperating with said first mentioned threads, a screw member extending through said flange and provided with an external thumb piece and provided with an internal screw-threaded portion, and a clamping member operated by said screw and engaging the neck of said reflector whereby said clamping member may be drawn into binding engagement with the neck of said reflector to thereby prevent rotation of said neck with respect to said flange.

3. An assembly of a head and reflector for a lamp comprising a head provided with means for receiving a lamp and provided with a downwardly extending internally threaded flange, a reflector provided with an externally threaded neck cooperating with the internal threads of said flange, a guiding member carried by said flange and projecting inwardly thereof, a clamping member carried by said guiding member and adapted to engage the neck of said reflector, and an externally operable screw for moving said clamping member into and out of engagement with said neck.

4. An assembly of a porcelain head and reflector for a lamp, said assembly comprising a porcelain head having a downwardly projecting internally threaded flange, a reflector having a threaded neck adapted to be screwed into said flange, said flange having a slot extending upwardly thereof and opening inwardly of said flange, a guide seated within said slot and projecting inwardly of said flange, a clamping member adapted to engage said neck and slidably carried by said guide, a screw member threaded into said

clamping member and projecting through said flange.

5. An assembly of a porcelain head and reflector for a lamp comprising a porcelain head having a downwardly extending internally threaded flange, said flange having a slot extending upwardly from its lower edge and opening inwardly of said flange, a guiding member having a base portion seated 10 within said slot and having a guiding portion projecting inwardly of said flange, a shaft holding said guiding member in assembled position within said slot and projecting through said flange and having a threaded portion located inwardly of said flange, a clamping member slidably carried by the guiding portion of said guiding member and screwed upon the threaded portion of said shaft, and a reflector having a threaded neck cooperating with the threads of said flange and adapted to be clamped by said clamping member when said shaft is rotated.

In testimony whereof, the signature of the inventor is affixed hereto.

25 ALWIN G. STEINMAYER.
